UNITED STATES PATENT OFFICE.

CARL G. THURNAU, OF NEW HARTFORD, NEW YORK.

WORKMAN'S SADDLE BELT.

Application filed January 8, 1926. Serial No. 79,955.

My present invention relates to workmen's saddle belts meaning thereby saddle and belt-like devices whereby workmen are suspended at the end of a rope.

5 The purpose of my invention is to provide a new and improved saddle belt and one which is capable of being safely and conveniently used by many classes of workmen.

10 Heretofore workmen have been suspended in dangerous places by being simply seated upon a board or chair seat attached to the supporting rope. Such devices were unsafe as they required the man to keep fairly bal-

15 anced in the swing or chair seat and required the constant use of one hand to keep him from sliding or falling from the seat. Such devices furthermore were very inefficient as far as the amount of work that 20 could be done by workmen was concerned in that the man had to hang on to the supporting rope with one hand and so had only one hand to work with. The attempt to use even temporarily the second hand in the 25 real work might readily result in injury or fatal accident to the workman.

The purpose of my invention is to provide a saddle belt which entirely obviates the dangers above mentioned and enables 30 the workman to have the free and unrestricted use of both hands and furthermore even allows him to fairly use his body in the work or to lean backward or to either side without possibility of danger.

35 A further purpose of my invention is to provide a saddle belt which normally supports the person in a sitting position comfortably and without strain, but which saddle belt is of such construction that the 40 workman may safely and comfortably lean back or to either side as he wishes.

A further purpose is to provide a device of the character described which can be very readily and safely attached to the body 45 or removed therefrom.

Fig. 1 is a front elevation of a saddle belt embodying my invention.

Fig. 2 is a perspective view of said device as seen from the rear and looking somewhat 50 down upon the device.

Referring to the drawings in a more particular description it will be seen that the device comprises a main supporting ring 5, a waist belt 6 and a pair of leg-supporting straps 7.

The main supporting ring 5 is preferably

formed as indicated in the drawing with three upwardly projecting separate eyes namely eye 8 at the center and eye 9 at the right and eye 10 at the left as the ring is seen from the front in Fig. 1. It will be understood that the ring and its three eyes are conveniently made from a single piece of strong iron providing a very rigid ring and a group of supporting eyes. One or 60 more of the eyes may be attached to the hook of the block through which the suspending rope or cable passes or the rope may be fastened direct to one or more of the eyes. The plurality of eyes is a convenient 65 arrangement when as often happens the workman is suspended from the lower end of two ropes which are separately adjusted as when a painter is working upon a diagonally arranged brace of a bridge or gas tank. The extra eyes also enable the workman to safely change from one suspending 70 rope to another by hooking on to the new rope before he disconnects from the old 75 rope.

The belt 6 is made of flexible material 80 preferably leather and has its opposite ends detachably secured to the opposite sides of ring 5. Such detachable connection is preferably effected by means of strong hooks 11 85 having their hook openings normally closed by spring tension keepers 12. The base or strap ends of these hooks are forked or provided with two spaced ears 13 connected 90 near their ends by a strong rivet or bolt 14.

An end of the belt is led through the opening between the shank of the rivet 14 and the opposing base of the hook and then bent back upon the body of the belt and strongly sewed or riveted thereto. In this 95 way the hook as a unit can freely swing upon its end of the belt enabling the workman to readily attach or detach the hook to or from the ring 5.

100 Preferably as shown in the drawing the central portion of the belt will be made much wider than its ends in order to more comfortably support the back of the workman and also to prevent any tendency of the belt to turn over or become twisted.

105 Depending from the belt there may be provided several small spring hooks 15 resembling generally the hook 11 already described but much smaller in size. These hooks 15 may be secured by a loop of leather 16 sewed or riveted to the belt. These hooks afford convenient means for 110

carrying tools or material for the workman.

Each of the two leg-supporting straps 7 preferably has its inner end secured to the ring 5 by means of a common shackle 17. 5 This is loosely, that is swingingly, but permanently mounted upon the ring with the said inner ends of the straps 7 going about the pin 18 of the shackle 17 and coming below said shackle pin where the different 10 layers of leather are securely fastened as by stitching.

The other ends of these straps 7, that is the outer ends, are loosely that is swingingly, but detachably connected to the ring 5 15 preferably by hooks 20 having spring keepers 21 and forked bases composed of spaced ears 22 connected by pins 23 all as described in connection with the belt hooks 11 and similar parts thereof. Through the space 20 between the pin 23, the ears 22 and the base of the hook 20 is led the extremity of one of the straps 7 with said extremity bent back upon the adjacent portion of the belt and securely fastened thereto as by a series of 25 stitches or rivets or both.

It will be understood that the loop of leather at the outer end of the leg strap 7 encircling the pin 23 of the hook 20 is larger in inside diameter than the pin and is a little narrower in width than the space between the ears 22 so that the hooks can be very readily swung about on the straps enabling the workman to readily attach or detach said hook and generally providing a free joint at 30 either point for freedom of motion in various ways. In the same way the inner ends of the leg straps are mounted for free movement upon the common shackle 17 and the hooks 11 for free movement upon the opposite 35 site ends of the belt.

Preferably about the middle half of each leg strap 7 may be appreciably widened say to a width twice that of the ends of the straps. This wider portion of the leg strap 40 is the part on the lower half of the leg and so provides a larger seat as it were for the person using the device. These two wide straps of say five or six inches at least in width below each leg in conjunction with 45 the increased width of the belt provide a very comfortable and convenient seat for the workman when he is suspended in mid-air on with one of these devices. As the belt and leg straps are not directly attached to 50 each other it will be seen that the user of the device can lean to one side or the other to almost a horizontal position and still be well supported in the device. Also it will be seen

that the user can lean backward as far as needed to carry on work. In these different 60 positions and many intermediate ones to which a painter or a similar workman may move his body the saddle belt here shown supports the user so comfortably and so securely that he can do much more work in a day and 65 particularly is free from any nervous strain. He does not have to worry for fear that he may inadvertently let go of the suspending rope and so lose his balance.

What I claim as new and desire to secure 70 by Letters Patent is:

1. In a workman's saddle belt the combination of a rigid ring for the attachment of a supporting rope, a waist belt detachably secured to said ring and two leg straps each 75 adapted to separately pass below and support one leg between the crotch and the knee, each of said straps having an end swingingly secured to the said ring and its other end detachably secured to the said ring. 80

2. In a workman's saddle belt the combination of a rigid ring having an upwardly projecting eye thereon for the attachment of a supporting rope, a waist belt detachably secured to said ring and two leg straps each 85 adapted to separately pass below and support one leg between the crotch and the knee, each of said straps having an end swingingly secured to the said ring and its other end detachably secured to the said ring. 90

3. In a workman's saddle belt the combination of a rigid ring having a plurality of upwardly projecting eyes thereon for the attachment of a supporting rope, one of said 95 eyes being located laterally of the other eye, a waist belt detachably secured to said ring and two leg straps each adapted to separately pass below and support one leg between the crotch and the knee, each of said straps having an end swingingly secured to the said ring and its other end detachably secured to the said ring. 100

4. In a workman's saddle belt the combination of a rigid ring for the attachment of a supporting rope, a waist belt having its opposite ends detachably secured to said ring and two leg straps each adapted to separately pass below and support one leg between the crotch and the knee, each of said 105 straps having an end swingingly secured to the said ring and its other end detachably secured to the said ring. 110

In witness whereof I have affixed my signature, this 18th day of May, 1925.

CARL G. THURNAU.
